UNITED STATES PATENT OFFICE.

CHARLES D. SIGSBEE, OF WASHINGTON, DISTRICT OF COLUMBIA.

TRUNK HINGE AND STAY.

SPECIFICATION forming part of Letters Patent No. 241,078, dated May 3, 1881.

Application filed March 21, 1881. (No model.)

To all whom it may concern:

Be it known that I, CHAS. D. SIGSBEE, a citizen of the United States, residing at Washington, District of Columbia, have invented new and useful Improvements in Trunk Hinges and Stays, of which the following is a specification.

My invention relates to certain novel features of construction in trunk stays and hinges, and has for its object economy and simplicity of construction coupled with positiveness and security of action; and with these ends in view my invention consists of a combined trunk hinge and stay, in which the leaves of the hinge are formed with keepers or stirrups, and provided with a sliding stay-link adapted to sustain the lid when open and strengthen the hinge when closed.

My invention further consists in the special details of construction hereinafter described and specifically claimed.

In order that those skilled may readily understand the construction and operation of my improved hinge, I will proceed to describe the same in detail, referring by letters to the accompanying drawings, in which—

Figure 1 is an end elevation of a part of a trunk with my improved hinge applied and sustaining the lid in an open condition. Fig. 2 is a perspective view of one form of my improved hinge. Fig. 3 is a similar view of a simple stay embodying my invention, being the same in construction as that shown at Fig. 2, with the central or hinge portion omitted; Fig. 4, a similar view of a modified form, in which the ends of the two leaves of the hinge are bent outward and over to form the link-keepers, and then flattened down against the body of the leaf; Fig. 5, a similar view of the construction shown at Fig. 4, with the central or hinge portion removed to form a simple stay; Fig. 6, a perspective view of the form shown at Fig. 4, with the ends of the leaves bent backward instead of outward, as shown in said figure; Fig. 7, a perspective view of the form shown at Fig. 3, with one of the "keepers" or "stirrups" slotted or cut away centrally, to permit the passage of the free ends of the wire link, as clearly shown; Fig. 8, a perspective view of the form shown at Fig. 2, and 50 with the same sort of a slot as shown at Fig. 7; Fig. 9, a perspective view of a hinge and

stay in which one leaf is formed with a pivotal bearing for the link, and the other with keepers or stirrups of necessarily increased length; and Fig. 10 is a perspective view of a simple stay, which may be made of two cast-iron keepers or stirrups and a bent wrought link.

In all the figures of the drawings similar parts are denoted by like letters of reference.

The hinge is formed of two wrought-iron leaves, A B, each adapted to the pintle-connection at C, and having their free ends bent to form keepers or stirrups D for a wire link or stay, E, and then extended at F to furnish stock for screw or rivet holes, by which the hinge may be secured to the body and lid of the trunk. When made in the form shown at Fig. 2 of the drawings—which is the one applied at Fig. 1—a piece, G, of thin metal is placed between the hinge and the trunk, to take up the frictional wear of the link; but when made in the forms shown at Figs. 4 and 6 the friction-plate is not necessary, as is obvious by visual inspection, and when made in the forms just referred to, and in order that the extreme outer ends of the hinge may be firmly attached to the trunk, a tongue, H, is formed by punching the same out of the stock forming the front of the keepers or stirrups D. The link may have its ends welded or otherwise connected, and the end 80 bars put into place within the keepers or stirrups D before the hinge or keepers are secured to the trunk; or they may be left disconnected, so that they may be sprung apart either to insert or remove the link; or, as shown at Figs. 7 85 and 8, the ends of the link may be bent into the form there shown, and projected through slots or longitudinal openings I, in which case the ends of the link serve to hold it against accidental displacement in an obvious manner. 90

When the leaves A B of the hinge are bent outward or backward, as shown at Figs. 5 and 6, the extreme end portions may be extended coincident with the flat portion of the hinge only far enough to furnish stock for two screw 95 or rivet holes; or they may extend down to the pintle or pivot C, and a greater number of screw or rivet holes made therein.

It will be understood that any desirable number of screws or rivets may be used to secure 100 a permanent attachment to the trunk.

When the trunk-lid is raised or opened, as

illustrated at Fig. 1, the end bars of the link E will come in contact with the outer ends of the keepers or stirrups of the leaves A, B, and thus securely hold the lid against undue backward movement, the lid being firmly braced by the link E against the back of the trunk; and when the lid is closed the link will assume the position shown in the other figures of the drawings, the end bars approaching the center of the hinge and coming in contact with the inner ends of the keepers or stirrups, the side bars lying outside of the edge of the hinge; and when in this position it will be observed that the link, being in contact with the inner ends of the keepers or stirrups, serves to relieve the pintle of the hinge from any undue strain, and securely locks the back edge of the lid against any upward movement, thereby greatly strengthening the hinge, and even should the hinge break at its joint the lid of the trunk would be securely held by the stay-link. The position of the side bars of the link along the edges of the hinge serves to protect the hinge, and vice versa, and the movement of the end bars in the keepers or stirrups will tend to straighten out or remove any indentations which might be made by the rough handling of the trunk. The keepers or stirrups are open at the sides, as clearly shown, so that the link may be readily secured in place from the back or edges of the hinge in an obvious manner, and they may or may not extend entirely across the leaves of the hinge, though I prefer the former construction, in order that an ordinary rectangular link may be used, which may be put in place before or after the hinge is secured.

When one end of the link is simply pivoted or journaled to one of the leaves of the hinge, as shown at Fig. 9, the keeper or stirrup at the end of the other leaf must necessarily be longer than when each leaf is formed with a keeper, and both ends of the link are free to move longitudinally; and while I have shown the form of connection shown at Fig. 9, I prefer the two keepers shown in the balance of the figures, for the reason that by the apportionments of the necessarily raised surface each one offers less surface to be indented by rough handling, thus decreasing the liability of damage.

While my invention relates, essentially, to

a combined hinge and stay, I have shown the various forms of keepers or stirrups disconnected from the pintle portion of the hinge, in order that when connected by the link they shall form a simple stay, which may be used independently of the hinge or applied to trunks furnished with other kinds of hinges, and I have taken pains to illustrate a series of modifications of my improved hinge and stay, in order that the broad principle of my invention may not be confounded with details of construction, the gist of my invention resting in the idea of so hinging the lid of a trunk that the lid shall be stayed or held in an open position, and when closed secured against upward movement; and while my invention contemplates, essentially, a trunk stay or hinge combined in one device, I desire to cover also the stay when separated from the hinge.

What I claim as new, and desire to secure by Letters Patent, is—

1. A trunk stay-hinge the leaves of which are formed with keepers or stirrups adapted to be entered by a stay-link from the side, substantially as and for the purposes set forth. 75

2. A wrought-iron hinge composed of leaves A, B, formed with keepers or stirrups D, in combination with a link, E, substantially as and for the purpose set forth. 80

3. The leaves A, B, returned upon themselves to form the keepers D, and metallic friction-surface, substantially as set forth.

4. The keepers or stirrups D, formed with the slot I, in combination with the link E, having its ends projected through said slot and bent down, substantially as and for the purpose set forth. 85

5. The keepers or stirrups D, connected by a link, E, to form a stay, substantially as and for the purpose set forth. 90

6. The securing-tongue H, formed from the stock of the keepers or stirrups D, substantially as and for the purpose set forth.

In testimony whereof I have hereunto set my hand in the presence of two subscribing witnesses.

C. D. SIGSBEE.
